UNITED STATES PATENT OFFICE.

HARRY SAWYER, OF MUSKEGON, MICHIGAN.

FREIGHT-HANDLING APPARATUS.

1,111,100.

Specification of Letters Patent. Patented Sept. 22, 1914.

Application filed May 19, 1913. Serial No. 768,666.

To all whom it may concern:

Be it known that I, HARRY SAWYER, a citizen of the United States, residing at Muskegon, county of Muskegon, State of Michigan, have made a certain new and useful Invention in Freight-Handling Apparatus, of which the following is a specification.

This invention relates to apparatus for handling freight, cargoes or the like.

10 The object of the invention is to provide a freight handling apparatus which is simple in construction and efficient in operation.

A further object is to provide an apparatus of the nature referred to wherein is employed a crane structure, including a vertically swinging boom and a horizontally movable frame from which the boom is pivotally suspended, and in connection therewith track systems which will permit the 20 operation of a trolley to and from the boom from and to a track system on a pier, or in a shed, warehouse, freight house or the like, and to secure proper registering relation of different portions of the track systems.

25 A further object is to provide an apparatus of the nature and character referred to wherein provision is made to prevent imposing an undue load upon the boom, as, for instance, to prevent more than one loaded trolley from operating upon the boom at any one time.

30 A further object is to provide an apparatus of the nature and character referred to wherein provision is made for the travel of a trolley in continuous direction while operating to and from the outer or free end of the boom.

35 Other objects of the invention will appear more fully hereinafter.

The invention consists substantially in the construction, combination, location and relative arrangement of parts, all as will be more fully hereinafter set forth, as shown 45 in the accompanying drawings, and finally pointed out in the appended claims.

Referring to the accompanying drawings and to the various views and reference signs appearing thereon,—

50 Figure 1 is a view in side elevation of a freight handling apparatus embodying the principles of my invention. Fig. 2 is a diagrammatic top plan view showing the track arrangement employed in connection with the apparatus shown in Fig. 1. Fig. 3 is a view similar to Fig. 1 showing an

other construction of apparatus embodying the principles of my invention and which, for many purposes, I prefer to use. Fig. 4 is a view similar to Fig. 2 showing the track and electric circuit arrangement and control employed in connection with the construction shown in Fig. 3. Fig. 5 is a broken detail view showing the circuit control arrangement for preventing two or more trolleys from operating on to the boom at the same time.

The same part is designated by the same reference sign wherever it occurs throughout the several views.

In the use of apparatus for handling freight, and particularly apparatus employed for loading or unloading boats, lighters, or other vessels, trains or the like, when lying alongside piers, docks, sheds, 70 warehouses, freight houses or the like, it is frequently difficult to bring a particular hatch, door or other opening of the boat, car or the like, into proper or convenient relation to the door, freight or other 75 opening of the pier or dock shed, warehouse or other building to or from which the cargo is to be delivered. And where power mechanism is employed for hoisting and transporting the freight or cargo to or from the boat, car or the like to be loaded or unloaded, it is desirable to 80 employ a track system in the shed or building and on or in connection with the crane and its boom along which a trolley or telpher carrying the freight or cargo may operate. In such case it is not always convenient or 85 possible to enable the track system in the building or shed to properly register with that of the crane structure while permitting 90 the boom or crane to serve a particular car or boat hatch, or a particular building or shed door opening. Again, where a boom of the overhanging type is employed it is 95 desirable to avoid imposing undue weight 100 thereon, as might be the case if two or more loaded trolleys were permitted to operate thereon at the same time, and in the expeditious operation of such apparatus it is 105 desirable to operate the trolleys in continuous or uniform direction while on the overhanging boom, thereby enabling such trolley to pass from the shed or building out to the extreme end of the boom and back again to the building without having 110 to change the direction of its movement.

It is among the special purposes of my

present invention to provide means for avoiding the objections noted and to attain the results and advantages stated.

In the accompanying drawings, I have 5 shown various means for carrying out my invention.

Referring to Figs. 1 and 2, reference numeral 6 designates, for instance, a pier or dock and 7 a supporting framework thereon.

- 10 This may be merely a supporting frame, or a pier shed or building or a portion thereof, may serve the desired purpose. The frame or building 7 is provided with a track system indicated at 8, which may be of any 15 suitable type and convenient arrangement, but preferably, though not necessarily this track system is of the overhead suspended I-beam type along the lower flange of which a hoisting trolley or telpher 9 is to operate.
- 20 Associated with the track system 8 are spurs or portions 10, 11, see Fig. 2, respectively arranged, for illustration, to extend from the track system inside the shed or building through various doors or openings therein 25 through any one or more of which the trolley is to operate. Upon the frame or building 7 are supported trackways 12, along which operate the supporting wheels 13, of a crane frame 14. Upon this crane frame is 30 carried the power mechanism indicated at 15, for swinging the boom presently to be referred to. The crane frame 14 carries a vertically extending tower 16, at the side thereof which is farthest from the building, 35 and the upper end of this tower is suitably held by a tension member 17, to the inner side or edge of the crane frame 14. The boom, indicated generally at 18, is pivotally connected at its inner end, as at 19, to the outer edge or side of the crane frame so as 40 to rock or swing vertically thereon, as indicated by dotted lines in Fig. 1. When the boom is in horizontal position for use its outer end is supported by linked rods 20, connected thereto and to the upper end of 45 the tower 16. The boom 18, in the arrangement shown in Figs. 1 and 2, carries a series of short track sections 21, and also a single movable track section 22, the latter 50 designed to be moved into coöperating relation with respect to any desired one of the sections 21, as clearly indicated in Fig. 2. The track sections 21, 22, are shown as being 55 of the suspended I-beam type with the trolley 9, designed to run along the lower flanges of the I-beam.

In use the crane frame 14 is moved along its tracks 12 until one or another of the track sections 21 on the boom is brought into line 60 with a spur track section 10, 11. The track section 22 is then brought into line with the particular section 21 which registers with the spur. The trolley may then operate along the boom to and from the building or 65 shed and the aligned track sections thereof.

In Figs. 3, 4 and 5, I have shown another construction and arrangement embodying my invention wherein provision is made for the operation of trolleys in continuous direction, thereby avoiding the delay incident to 70 operating them in opposite directions over the same track, and also wherein a system of current supply and control is arranged which prevents more than one trolley from operating upon the overhanging portion of 75 the boom at the same time. In this arrangement I employ the same arrangement and spacing of tracks in the building, or shed, but double the number of track sections 23, are employed as in the case of the sections 80 21, above described, and the track sections 23 are so spaced apart that when one of them, say the first, is brought into register with a spur track 11, for instance, another, say the sixth, is brought into register with the next adjacent spur 10. This same relation is maintained between the second and seventh, the third and eighth, and so on. Instead of a single straight, movable track section, as in the case of the section 22, 85 above described, a boom track section 24, is employed which is formed into a loop with its ends spaced apart to correspond with the inter-spacing of the track sections 23. That is to say when one end of the loop 90 section is in register, with the first section 23, the other end of said loop is in register with the sixth section 23, and so on. This arrangement makes a complete loop track and enables the trolley to run out on spur 100 section 11, for instance, then to the first of the series of sections 23, thence to and along the loop track 24, to the sixth of the sections 23, to the spur track section 10, and the building or shed track system. 105

In order to enable the boom to serve a particular hatchway, or door which might not be located opposite track sections, 10, 11, the loop track section 24 on the boom is made shiftable. To this end said loop 110 track section is carried on the underside of a frame 25, which is pivotally connected, as at 26, see Fig. 4, concentric with the circular portion 27 of the loop to the boom framing. The frame 25, or portions thereof, project 115 over a track rail 28, supported in the main boom frame, which rail is curved to an arc concentric with the pivotal axis 26 of the frame 25. Wheels 29, see Fig. 5, carried by frame 25 operate along the rail 28, and thus 120 serve to support the frame 25, as well as the loop track and trolley when the weight of the latter is imposed on the loop track.

I will now describe a wiring arrangement and control therefor, for supplying propelling current to the trolley operating motor, and by means of which two or more trolleys are prevented from being on the loop track section at the same time while permitting trolleys to follow each other in close succes- 130

sion in the expeditious handling of freight. Each spur track section 10, 11, as well as each track section 23, and the loop section 24, is provided with a supply and a return conductor, circuit between said conductors being completed through the trolley and its propelling motor, when the trolley is operating along either of said track sections. A supply or positive conductor *a*, is connected to one member of each pair of conductors with which each track section 23 is equipped. Similarly, a return or negative conductor *b*, is connected to the other member of said pairs of track section conductors. The conductors *a*, *b*, are connected respectively through the feed and return conductors *c*, *d*, with any convenient service mains or other conductors, *e*, *f*. A switch device, indicated generally at 30, Fig. 3, affords means for controlling the connection between conductors *a*, *b*, and feeders *c*, *d*. When this switch is open, current will be supplied only to the pair of loop track conductors, 31, 32, which are respectively in electrical communication with the feeders *c*, *d*, at the points 33, 34. When the switch 30 is closed then current will be supplied to the pairs of conductor sections of all the track sections 23, as well as to that of loop track section 24. The switch 30, may be operated by a rock shaft 35, having arms 36, 37 at the respective ends thereof. These arms are so relatively arranged that they extend or may be brought into the path of a trolley as the latter enters upon or leaves the loop track section 24, that is, as the trolley passes from a track section 23, onto the loop track 24, it engages say arm 36, on shaft 35, and rocks said shaft, thereby opening the switch 30. Thereupon current will not be supplied to the track rail sections 23, but there will be no interruption of the current supply to the loop track conductors 31, 32. At the same time, arm 36 is rocked to open the switch 30, the arm 37, at the other end of the shaft is brought into the path of the trolley to be engaged thereby and rocked as the trolley passes from the loop track section onto a track section 23, thereby 50 rocking the shaft 35 in the opposite direction to close the switch 30. The closing of this switch reestablishes current supply to the conductors of track sections 23. Thus it will be seen that while the trolleys are permitted to follow each other in close succession, two of them cannot be on the loop track section at the same time, the travel of one onto the loop automatically preventing the next succeeding one from proceeding, but this prevention is removed as the first one leaves the loop.

From the foregoing description it will be seen that it is not necessary for the boom to be in exact line with a spur track section 10, 11. It is sufficient if any coöoperating pair

of the track sections 23 are brought into registering relation with any two corresponding spur sections 10, 11, and then the loop track section 24, will be swung into corresponding position to coöperate therewith. 70 It will also be seen that the boom, when in horizontal position for use is supported at its outer end by the jointed rods or links 20.

Having now set forth the objects and purposes of my invention and embodiments of 75 the principles thereof, what I claim as new and useful and of my own invention, and desire to secure by Letters Patent, is—

1. In an apparatus for handling freight, an elevated structure having a track system 80 including spur sections, a crane frame movable transversely of said spur sections, a boom pivotally suspended from said crane frame, a plurality of track sections carried by and extending longitudinally of the 85 boom and respectively adapted to register with said spur sections, and a track portion also carried by the boom and movable to coöperate with any one of said track sections.

2. In an apparatus for handling freight, 90 an elevated structure having a suspended overhead track system including spur sections, a crane frame carried by said structure and movable transversely of said spur sections, a boom pivotally suspended from 95 the crane structure, a plurality of track sections suspended from and extending longitudinally of said boom and adapted to be brought into register with said spur track sections to coöperate therewith, and a track 100 portion also suspended from said boom and movable to coöperate with any one of said track sections.

3. In an apparatus for handling freight, 105 an elevated structure having a track system, including spur sections suitably spaced apart, a crane frame mounted to move in a direction transverse to the length of the spur sections, a vertically swinging boom suspended from said crane frame, a plurality of track sections carried by and extending longitudinally of said boom and suitably spaced apart, said track sections co-operating with the spur sections when brought into register therewith by shifting 110 said crane frame, and a track section carried by the boom, and movable to register with any desired one of said track sections.

4. In an apparatus for handling freight, 120 a track system, a crane frame, a boom carried thereby, a plurality of track sections carried by the boom, said crane frame being movable relatively to the track system to bring the track sections and track system into coöperative relation, and a track portion carried by the boom and independently movable to coöperative relation with any one of the track sections.

5. In an apparatus for handling freight 125 a track system, a crane frame, a vertically 130

swinging boom pivotally suspended from the crane frame, a plurality of track sections carried by the boom, said crane frame being movable to shift said track sections relatively to the track system, and an independent track portion carried by the boom, and movable into coöperative relation with respect to any desired track section.

6. In an apparatus for handling freight, 5 an overhead track system, a crane frame, a vertically swinging boom pivotally suspended from the crane frame, a plurality of track sections suspended from said boom, said crane frame being movable to shift said track sections relatively to the track system whereby any desired track section may be brought into alinement with the track system, and a track portion suspended from said boom, said track portion being independently movable relatively to said track sections to aline with any desired track section.

7. In an apparatus for handling freight, 25 a track system, a crane frame, a boom carried by said frame, a plurality of track sections carried by said boom and arranged to coöperate in pairs with said track system, and a track portion also carried by said boom and arranged in the form of a loop to coöperate with corresponding pairs of said track sections.

8. In an apparatus for handling freight, 35 a track system including spur sections suitably spaced apart, a crane frame, a boom carried thereby, a plurality of track sections carried by said boom and arranged in co-operating pairs corresponding in distance apart to the spur sections, said crane frame being movable to bring the corresponding 40 track sections into register with the spaced spurs, and a loop shaped track section movably mounted on the boom and having its ends arranged to coöperate with said pairs of track sections.

45 9. In an apparatus for handling freight, a track system, a crane frame, a boom carried thereby, a plurality of track sections carried by said boom and spaced apart in co-operating pairs, said crane frame being movable to shift coöoperating pairs of the track sections into registering relation with the track system, and a loop track portion carried by said boom and movably mounted thereon to coöperate with said pairs of track 50 sections.

55 10. In an apparatus for handling freight, a track system, a crane frame, a boom pivotally suspended from said frame, a plurality of track sections carried by the boom, said crane frame being movable to shift co-operating pairs of said track sections into registering relation with the track system and a movable loop track also carried by the boom and coöperating with said track 60 sections.

11. In an apparatus for handling freight, 75 a track system including spurs spaced apart from each other, a movable crane frame, a boom carried thereby, a plurality of converging track sections carried by the boom and coöperating in pairs with said spurs and a loop track section also carried by the boom, said loop track section being movable to bring the ends thereof into coöperation with corresponding pairs of track 75 sections.

12. In an apparatus for handling freight, 80 a track system including spurs, a movable crane frame, a vertically swinging boom pivotally suspended therefrom, a plurality of 85 track sections carried by said boom and arranged to coöperate in pairs with said track system spurs, a loop shaped track portion pivotally mounted upon the boom and movable to bring the ends thereof into register 85 with coöperating pairs of track sections.

13. In an apparatus for handling freight, 90 a track system, a movable crane, a vertically swinging boom pivotally suspended from said frame, track sections carried by 95 said boom and coöperating with the track system and a loop shaped track also carried by said boom, a supporting frame therefor, said supporting frame being pivotally supported on the boom. 95

14. In an apparatus for handling freight, 100 a track system including spurs, a crane frame, a boom pivotally suspended therefrom, track sections carried by said boom, a guiding rail, a frame pivotally mounted 100 upon the boom and operating along said guide rail and a loop shaped track section carried by said last mentioned frame.

15. In an apparatus for handling freight, 105 a track system, a crane, a boom carried by said crane, track rail sections carried by the boom and coöperating with the track system, current supply conductors associated with said track rail sections and means actuated by a trolley when operating along a 110 portion of said track section for opening the circuit of the conductors associated with the other portion of the track sections.

16. In an apparatus for handling freight, 115 one of said sections being movable into co-operative relation with respect to the others, current supply conductors associated with said track sections, a switch for opening and closing the circuit of said supply conductors to one or another of said track sections, and means operated coincidently by the passage of a trolley from one to another of said track sections for operating said switch. 120

17. In an apparatus for handling freight, 125 a track system, a crane, a boom carried by said crane, track rail sections carried by said boom and coöperating with the track system, a loop track carried by the boom and 130

coöperating with said track rail sections, current supply conductors associated with said track rail sections and loop track, a switch operating to cut off current supply to the track rail sections without affecting current supply to the loop track conductor, and means operated by a trolley passing from a track rail section to the loop track for opening said switch.

10. 18. In an apparatus for handling freight, a track system, a crane, a boom carried thereby, track rail sections carried by the boom and coöperating with the track system, a loop track carried by the boom and co-
15 operating with said track rail sections, current supply conductors associated with said track rail sections and loop track, a switch operating, when open, to cut off current supply to the track rail sections without affecting current supply to the loop track conductor, means operated by a trolley passing from a track rail section to the loop track for opening said switch and means operated
20 by a trolley passing from the loop track to a track rail section for closing said switch.

25. 19. In an apparatus for handling freight, a track system, a crane structure, a plurality of track sections carried thereby to co-operate with the track system, a loop track

operating when open to cut off current supply to the track section conductors without affecting current supply to the loop track, a rock shaft for opening and closing said switch, and oppositely arranged rock arms carried by said shaft and respectively located in the path of a trolley passing to and from the loop track to open and close said switch.

20. 18. In an apparatus for handling freight, a track system, a crane structure, a plurality of track sections carried thereby to co-operate with the track system, a loop track also carried by the crane structure and co-operating with the track sections, current supply conductors associated with said track sections and loop track, means operated by a trolley passing from a track section to the loop track for cutting off current supply to the track section conductors without affecting current supply to the loop track conductor, and means operated by the trolley passing from the loop track to the track sections for closing the track section conductors to current supply.

In testimony whereof I have hereunto set my hand in the presence of the subscribing 60 witnesses, on this 10th day of May, A. D., 1913.

HARRY SAWYER.
